UNITED STATES PATENT OFFICE.

JOHN A. WESENER, OF CHICAGO, ILLINOIS.

METHOD OF MATURING AND BLEACHING FLOUR.

1,096,480.

Specification of Letters Patent.

Patented May 12, 1914.

Application filed June 2, 1913. Serial No. 771,252.

To all whom it may concern:

Be it known that I, JOHN A. WESENER, a citizen of the United States, residing at Chicago, in the county of Cook and State of Illinois, have invented certain new and useful Improvements in Methods of Maturing and Bleaching Flour, of which the following is a specification.

My invention relates to the art of maturing and bleaching flour by the use of a gaseous agent composed of a mixture of nitrosyl chlorid gas and chlorin; and the object of the invention is to provide certain improvements upon the method of using this agent for the treatment of flour disclosed in my Patent No. 863,684, art of bleaching and aging flour, granted August 20, 1907. The action of these two gases upon flour, as I have discovered by study and experiment extending over a period of several years, is peculiar and in some respects quite unexpected. Nitrosyl chlorid gas is an extremely powerful bleaching agent. A pound of the pure gas (measured in the liquefied form) will bleach in the neighborhood of two hundred thousand pounds of flour. The bleaching effect of chlorin gas is very considerably less. A pound of chlorin gas will bleach only from five to ten thousand pounds of flour. However, the action of the chlorin on the gluten in the flour is very marked and, when properly applied to the flour, very beneficial. It partially hydrolyzes or splits up the gluten making it more elastic and more responsive to the yeast and the gases of fermentation. As a result the baking qualities of flour properly treated with chlorin gas are improved. Flour thus treated produces a loaf of larger volume, finer texture and more uniform porosity than the untreated flour. On the other hand, nitrosyl chlorid gas, if used in moderate quantities, has little or no effect upon the gluten of the flour or upon its baking qualities. If used in sufficient quantities to act upon the gluten, instead of bleaching the flour, it gives it a reddish tint which is considered objectionable. Furthermore, the excessive use of this gas affects the chemical character of the oil with the result that after the flour has been kept for a time it becomes rancid. In view of these facts it is of the utmost importance, in order that the best results should be obtained, having regard both to the removal of the color from the

flour and the improvement in its baking qualities, that in applying the agent to the flour the proper proportions should be maintained between the nitrosyl chlorid and the chlorin. It is also important that the gaseous agent should be brought into contact with the flour in proper and controllable quantities. If uniformly good results are to be obtained it is very desirable also that the agent be free from impurities and practically anhydrous. The presence of impurities, besides having possible deleterious effects on the flour, makes accuracy of control impossible. If there be any appreciable amount of moisture in the gases acids will be formed which, besides decreasing the amount of the active agents, are in themselves injurious to the flour. These acids, if present in the gaseous agent, corrode the metal parts of the apparatus, the packing of the valves, and the like, and besides shortening the life of the apparatus, produce metal salts which are carried into the flour and injure and taint it.

Having these considerations in view, I have devised a method of treating the flour with nitrosyl chlorid gas and chlorin which is far superior to the method disclosed in my patent above mentioned. This method is based primarily upon the discovery which I have made that when nitrosyl chlorid gas and chlorin are liquefied and mixed together in the liquefied state no chemical action takes place which changes their individual characteristics, and upon the further discovery that although the boiling points of chlorin and nitrosyl chlorid are not the same, when these gases are mixed together in liquid form they will vaporize in constant proportions for all operative temperatures and pressures.

The gases are preferably made separately, liquefied, mixed together in containers and so supplied to the millers. The nitrosyl chlorid is preferably made by decomposing nitric acid by means of sulfur dioxid which gives nitric oxid and combining this with chlorin. Each gas is carefully dehydrated. The agent should not contain substantially more than two-tenths of one per cent. of moisture. By describing the gases as anhydrous I mean that they do not contain a substantially larger percentage of moisture than this. The liquefied gases are mixed together preferably in the proportion of one

to five parts of nitrosyl chlorid and ninety-nine to ninety-five parts of chlorin by weight.

Any suitable form of apparatus may be employed for applying the gaseous agent to the flour. I preferably make use of the apparatus disclosed in my pending application Serial No. 752,400, filed March 6, 1913.

The accompanying drawing shows diagrammatically and in simplified form an apparatus of this type.

A designates the treating chamber, flour being introduced into the same through a spout B and the treated flour being discharged through a spout C. Flour falls through cones D and is kept in agitation by means of disks E on a revolving shaft F.

G designates the container holding the nitrosyl chlorid and chlorin mixed in liquefied form. This mixture is vaporized, by opening valve H, and flows through the pipe I into the treating chamber. At the point it enters the treating chamber it is diluted by air from a pipe J connected with an air pump K. Preferably the extremity of pipe I extends into the end of pipe J as shown so that the gas is drawn out through the pipe I by the air current. By applying the air to the gas at the point the latter enters the treating chamber the formation of acids in the conductors is prevented even though the atmosphere should contain some moisture.

The amount of the gaseous agent used for treating a given quantity of flour will vary somewhat according to the character of the flour treated, the amount of coloring matter that it contains, and the quantity and character of the gluten. Flours containing a large amount of gluten or in which the gluten is tough and harsh, will require more treatment than flours made of softer wheat or wheat containing a smaller percentage of gluten. The amount of the agent for treating ten thousand pounds of flour will vary from one-fourth of a pound to one pound, measuring the gases in the liquefied state.

It will be seen that the hereinabove described method of employing nitrosyl chlorid and chlorin gases together for the bleaching and maturing of flour has several advantages over the method described in my prior patent above referred to and, I believe, over all methods of bleaching and maturing flour which have been heretofore used or proposed. The gaseous agent can be applied to the flour practically free from all impurities. This is not possible if the agent be manufactured chemically, electrically, or electrolytically, and brought into contact with the flour immediately as generated. It is also possible to accurately control the vaporization of the liquefied mixture and thereby regulate the quantity of the agent ap-

plied to a given quantity of flour. The gases when they come into contact with the flour are practically anhydrous which prevents the formation of acids that are both injurious to the flour and also wasteful of the gases themselves. The agent may be supplied to the miller with its constituents mixed in the proper proportions and in readiness to be used in an apparatus which is extremely inexpensive to install and easy to operate even by the unskilled.

The method of applying the gaseous agent to flour, as above described, might be practised with other agents than the mixture of nitrosyl-chlorid and chlorin gases; for example, the method is susceptible of being carried out with chlorin alone, nitrogen tri-oxid (N_2O_3) or bromin. I do not claim herein specifically the use of chlorin alone, as this is claimed in my copending application, Serial No. 749,493, filed Feb. 19, 1913 (patented September 2, 1913, in Patent No. 1,071,977).

I claim:

1. The process of maturing flour and removing the color therefrom which consists in applying to the flour in regulated quantities a gaseous agent formed by vaporizing a mixture of liquefied nitrosyl chlorid and chlorin gases.

2. The process of maturing flour and removing the color therefrom which consists in applying to the flour in regulated quantities a gaseous agent formed by vaporizing liquefied nitrosyl chlorid and chlorin gases mixed in such quantities that the nitrosyl chlorid does not constitute more than five per cent. of the mixture.

3. The process of maturing flour and removing the color therefrom, which consists in applying to the flour, in regulated quantities, a gaseous agent formed by vaporizing a mixture of anhydrous liquefied nitrosyl chlorid and chlorin gases.

4. The process of maturing flour and removing the color therefrom, which consists in applying to the flour, while in suspension in the air in an inclosed space, a gaseous agent formed by vaporizing a mixture of anhydrous liquefied nitrosyl chlorid and chlorin gases introduced into said inclosed space in the form of a stream and diluted by a stream of compressed air applied to the gas stream at the point the latter enters said space.

5. The process of maturing flour and removing the color therefrom, which consists in applying to the flour, while in suspension in the air in an inclosed space, a bleaching and maturing agent which is an active gas at ordinary temperatures and atmospheric pressure formed by gradually vaporizing a stored quantity of said agent in liquefied condition and introducing the gas into said inclosed space in the form of a regulated

stream, diluted by a stream of compressed air applied to said gas stream at the point it enters said space so as to break up said gas stream and thoroughly mix the gas with 5 air before it reaches the flour.

6. The process of maturing flour and removing the color therefrom, which consists in applying to the flour, in suspension in the air in an inclosed space, a gaseous agent in 10 the form of a thin stream surrounded by a stream of compressed air which operates to break up the gas stream and dilute the gas

with air before the gas comes into contact with the flour.

7. The method of treating flour to mature 15 and whiten it which consists in bringing into contact therewith, diluted with air, a bleaching and hydrolyzing gaseous agent obtained from an anhydrous source of supply.
